UNITED STATES PATENT OFFICE.

HENRY LOWERY, OF POMEROY, OHIO.

WHIP-FASTENER.

No. 907,514.

Specification of Letters Patent.

Patented Dec. 22, 1908.

Application filed May 29, 1908. Serial No. 435,784.

To all whom it may concern:

Be it known that I, HENRY LOWERY, a citizen of the United States, residing at Pomeroy, in the county of Meigs, State of Ohio, have invented certain new and useful Improvements in Whip-Fasteners; and I do hereby declare the following to be a full, clear, and exact description of the invention, such as will enable others skilled in the art 10 to which it appertains to make and use the same.

The invention relates to a whip fastener and is particularly adapted for use with a whip socket.

15 The primary object of the invention is the provision of a whip fastener insertible in a whip socket and having yieldable locking jaws between which is received a whip for securing the same in the whip socket, the 20 said jaws being partially surrounded or inclosed by an expansible coiled spring which latter when in a distended condition maintains the jaws in a closed or locked position and connected to the coiled spring is a pull 25 member projecting through one end of the whip socket whereby the member may be actuated to compress the spring so that the jaws will be automatically released.

Another object of the invention is the provision of a whip fastener by which a whip 30 may be readily locked or fastened so that it cannot be withdrawn without being released by the operator actuating a pull member to free the fastener from engagement with the 35 whip.

In the drawings accompanying and forming part of this specification is illustrated one form of embodiment of the invention which, to enable those skilled in the art to practice 40 the same, will be set forth at length in the following description, while the novelty of the invention will be included in the claims succeeding said description.

In the drawings:—Figure 1 is a longitudinal sectional view of a whip socket with the invention applied thereto and the yieldable jaw members in their closed position. Fig. 2 is a similar view showing the jaw members in their released or open position. Fig. 3 is a 50 transverse section. Fig. 4 is a top plan view with the whip socket in section. Fig. 5 is a bottom plan view with the whip socket in section. Fig. 6 is a side view of a pull member. Fig. 7 is a side view of the locking jaws, and the same being partly broken away. 55 Fig. 8 is a detail side view in section of the bridge piece.

Similar reference characters indicate corresponding parts throughout the several views in the drawings. 60

In the drawings, the numeral 10 designates a cylindrical body forming the whip socket proper and has a bottom 11 having a central perforation or opening 12 and within the cylindrical body are locking jaw members 13 65 each of semi-circular formation in cross section and which members have reduced flexible spreading arms 14 united at their lower extremities by a connecting piece 15 which holds the arms in spaced relation to each 70 other. This connecting piece 15 rests and has its bearing against the bottom 11 when the jaw members have been inserted through the mouth portion of the whip socket for operative position therein. Intersecting the 75 space between the arms 14 and lying against the inner face of the connecting piece 15 is a bridge piece 16 having opposite extensions 17 secured by screw fasteners 18 to the bottom 11 of the whip socket. 80

Surrounding the arms 14 and a portion of the jaw members 13 is a convoluted or coiled compressible spring 19 the lower extremity of which has its bearing against the bridge piece 16 and connected to the opposite extremity of the said compressible spring are eyes 20 formed at opposite extremities of a cross member 21 having a centrally depending stem or rod 22 which passes through corresponding openings 23 centrally of the 90 bridge piece 16 and connecting piece 15 respectively and which openings are in register with the opening 12 in the bottom 11 of the whip socket and which rod extends through the latter opening exteriorly of the whip 95 socket and terminates in a threaded extremity 24 to which is secured a detachable button 25, whereby the rod 22 may be pulled in an outward direction from the whip socket to compress the coiled spring 19 so that the 100 jaw members 13 will be released and be permitted to spread or separate a distance from each other to receive a whip and upon the release of said button 25 the coiled spring 19 will again become distended thereby automatically closing the jaw members 13 for locking engagement with the whip. It is 105 obvious that the bridge piece 16 centers the

jaw members 13 in the whip socket and fixedly maintains the whip fastener in position therein.

What is claimed is—

- 5 1. In a whip socket, a whip fastener comprising oppositely disposed yieldable jaws, a compressible spring surrounding the jaws for a portion of their length, and means for compressing said spring to release the jaws.
- 10 2. In a whip socket, a whip fastener comprising yieldable jaw members, a compressible spring upon said jaw members to close the same, and means projecting beyond the whip socket at one end thereof and connected to said compressible spring to actuate the same to permit the separation of the jaw members.
- 15 3. In a whip socket, a whip fastener com-

prising oppositely disposed locking jaw members having yieldable reduced arms united 20 at their lower extremity, a compressible spring surrounding the arms and a portion of said jaws, a bridge piece for securing the whip fastener in the socket and forming a bearing for one extremity of the compressible spring, a pull rod having connection with the opposite extremity of said spring and projecting exteriorly of the whip socket, and a button carried by the free end of said rod. 25

In testimony whereof, I affix my signature, 30 in presence of two witnesses.

HENRY LOWERY.
